UNITED STATES PATENT OFFICE.

FREDERICK A. FELDKAMP, OF NEWARK, NEW JERSEY.

FUSE CARTRIDGE.

Application filed August 23, 1919. Serial No. 319,303.

To all whom it may concern:

Be it known that I, FREDERICK A. FELDKAMP, a citizen of the United States, residing at Newark, in the county of Essex and 5 State of New Jersey, have invented certain new and useful Improvements in Fuse Cartridges; and I do hereby declare the following to be a full, clear, and exact description of the invention, such as will enable others 10 skilled in the art to which it appertains to make and use the same, reference being had to the accompanying drawings and to characters of reference marked thereon, which form a part of this specification.

15 The present invention has reference, generally, to improvements in fuse cartridges.

The invention has for its principal object to provide a novel means, in combination with the general fuse cartridge construction, 20 adapted to reduce and relieve sudden internal pressure within the fuse container, due to a sudden blowing of the fuse, thereby preventing bursting or rupture of the container and other attendant dangers.

25 Other objects of this invention, not at this time more particularly enumerated, will be clearly understood from the following detailed description of the same.

With the objects of my invention in view, 30 the same consists, primarily, in the novel construction of fuse cartridge hereinafter set forth; and, furthermore, the invention consists in the novel arrangements and combinations of the various parts, as well as in 35 the details of the construction thereof, all of which will be hereinafter more fully described and claimed.

The invention is clearly illustrated in the accompanying drawings, in which:—

40 Figure 1 is a longitudinal section of a fuse cartridge made according to and embodying the principles of my present invention; Figure 2 is an end elevation of the same; and Figure 3 is a cross-section through the same 45 taken on line 3—3 in said Figure 1.

Figure 4 is a longitudinal section of a slightly modified construction of my novel fuse cartridge. Figure 5 is a longitudinal section of a multiple fuse cartridge embodying the principles of my present invention.

50 Similar characters of reference are employed in the herein above described views, to indicate corresponding parts.

It is well known that upon the blowing of 55 the fuse element of a fuse cartridge by a short circuit, an internal pressure is created

within the cartridge or container, which is due both to vaporization of the fuse metal, as well as to the expansion by the generated heat of air present between granules of the 60 filler usually surrounding the fuse. This pressure is of considerable magnitude, and if not quickly reduced or relieved, may result in the bursting of the cartridge or at least in a serious rupture thereof. In order 65 to relieve the internal pressure created by the gases resulting from the vaporization of the fuse, it has heretofore been customary to provide escape openings or vents in the ends of the ferrules, and in order that 70 the granular filler substance should be prevented from falling or passing out through said openings or vents, washers or guards of asbestos or wire mesh, or perforated discs have been interposed between the end wall 75 of the ferrules and the granular filler substance. Such washers or guard devices, however, are not entirely satisfactory for the intended purpose, since, as in the case of asbestos washers, they are not porous enough 80 to readily admit of the quick penetration and passage of the gases therethrough, or as in the case of wire mesh or perforated discs, the interstices therein become so clogged or 85 choked up with the granular filler substance that the passages therethrough become impassable, thus counteracting the very function of venting the gases and relieving internal pressure desired to be accomplished.

Even in the event that the gases do reach the 90 vent openings of the ferrules, and pass outwardly therethrough, the same are in such a state of high temperature, that there is always danger of igniting inflammable material in the neighborhood of the fuse cartridge. That such is the case has been established by underwriter's tests in numerous instances.

It is the primary object of my present invention to combine in the structure of a 100 fuse cartridge a novel means whereby not only will the gases occurring after the blowing and vaporization of the fuse element be quickly liberated from the interior of the cartridge or container, but the same will 105 also be quickly reduced in temperature, all of which will result in a very rapid reduction of internal pressure within the cartridge or container, thus rendering the fuse cartridge much safer in use, and assuring 110 against bursting or rupturing of the same under the conditions above mentioned.

With this object in view my novel construction of fuse cartridge comprises a suitable tubular casing 1 made of some desired variety of insulating material, the same being closed at its respective ends by means of metallic ferrules 2, the same not only serving to close the interior chamber 3 provided by the casing, but also serving as electrical contact elements to be received in the clips 10 provided for holding the fuse cartridge in use, and electrically connected in the circuit to be served by the same. Centrally disposed relative to each ferrule 2, and secured to the end walls thereof by solder or other 15 suitable fastening means, are inwardly extending anchor studs or contact posts 4 to which are secured the respective ends of a fuse element 5 mounted to extend longitudinally through the said interior chamber 3. 20 The intermediate space of the chamber 3 about the fuse element 5 is filled with a granular filler-powder 6, such as is commonly employed in the construction of fuse cartridges. Disposed in the end portions of 25 the chamber 3, between the filler powder and the end walls of the ferrules 2, and extending for a considerable or substantial depth, are layers of metallic wool 7 or other metallic material adapted to provide a highly 30 porous mass, or a body of metallic material interspersed with a multiplicity of interconnecting interstices throughout its extent. I find that the substance which gives most excellent results, considering the purposes in 35 view, is what is known as steel wool, although I do not necessarily limit myself to the use of this material alone, since any metallic wool, the metal of which possesses a comparatively high melting point, or any 40 metallic shavings, filings or chips of comparatively high melting point, which when massed together provide the desired multiplicity of interconnected interstices may be used, and will serve more or less successfully 45 the purposes I have in view. The end walls of the ferrules 2, against the inner sides of which the said layers of metallic wool or the like abut, are provided with a number of 50 vent holes or perforations 8. In some cases it may be desirable to re-enforce or strengthen the end walls of the ferrules 2, in which case a disc 9 of metal or other suitable material may be arranged and suitably secured against the inner side of said end 55 walls of the ferrules 2, said disc 9 being provided with vent holes or perforations 10 to register or aline themselves with the vent holes or perforations 8 of the ferrules, all of which is more particularly illustrated in 60 figure 4 of the drawings. While I have described the layers 7 of steel wool or other suitable material as disposed at each end of the chamber 3 intermediate the filler powder 6 and the ferrules 2, if desired, the same 65 may be omitted at one end of the chamber

so as to establish but one end of the chamber as a venting point. In such case the filler powder 6 will extend directly to the ferrule at one end of the chamber 3, the vent holes or perforations 8 being omitted from said 70 ferrule thus engaged by the said filler powder.

Referring now, more particularly, to Figure 5 of the drawings, I have shown therein how the principles of my present invention 75 may be applied to a multiple fuse cartridge, such, for example, as is in my prior application for Letters-Patent, filed March 31, 1917, and bearing Serial No. 158,809, resulting in Patent No. 1,268,807. In this view 80 the reference character 11 indicates the tubular casing having a fixed ferrule 12 at one end, and a movable ferrule 13 at the opposite end. Arranged in that end of the casing bearing the movable ferrule 13 is a plug 14 85 in which is imbedded the fuse contact pins 15 with which the contact element 16, carried by the movable ferrule 13, may be selectively engaged to bring into the circuit any desired one of the fuse elements 17 extending respectively from said contact-pins 15. Suitable partition members 18 are provided to enclose each fuse-element 17 in its own individual compartment. Connected with said fixed ferrule 12 is an inwardly extending common contact-post 19 with which the several fuse elements 17 are connected to electrically engage the same with said fixed ferrule 12. The partition members 18 terminate short 90 of the end wall of said fixed ferrule 12 leaving an annular free space about the shank of said contact post 19. The several elements 17 are each surrounded in their respective compartments with the usual granular filler powder 20, which also extends 95 partially into the annular free space above mentioned. Arranged in said annular free space, between the filler powder 20 and the end wall of said fixed ferrule 12 is a layer 100 of steel wool or the like 21, and the said end wall of the fixed ferrule is provided with one or more vent holes or perforations 22. 105 When a fuse cartridge constructed according to the principles of my present invention is blown, the heat expanded air and the gases resulting from the vaporization of a portion of the fuse metal immediately gives rise to an internal pressure within the casing. The expanded air and gases are forced by this pressure through the filler powder, and are driven into the layer of metallic wool or the like penetrating and passing through the interstices thereof until the vent holes or perforations in the adjacent ferrules are reached, through which 110 they are passed into the external atmosphere. By passing through the interstices in said layer of metallic material, the temperature of the air and gases is quickly reduced by contact with the comparatively 115 120 125 130

cool metal, and consequently the volume thereof is diminished as they cool, thereby immediately tending to reduce the pressure from such cause, as well as by the reduction of their volume due to the ejection thereof through the vent holes or perforations of the ferrules. Another advantage of the layer of metallic wool or the like is that the same is more or less elastic as to its mass, and consequently cannot be choked up with filler powder, since the interstices formed extend in all directions, and new openings or passages for the gas open up around such particles of powder as may possibly penetrate the metallic wool for a short distance, so that the gas may always find a point of escape. In this respect my arrangement is much superior to perforated or wire mesh washers or discs, the interstices of which all extend in one direction so that the powder may very quickly penetrate the same and quickly choke them up, thus obstructing the desired venting of the gas. Furthermore, the perforated or wire mesh washers or discs do not successfully bar the escape of some powder therethrough when handling the fuse cartridges, whereas the layer of steel wool or the like provides such a multiplicity of devious passages that the powder can not penetrate through the same in a straight line and consequently is soon blocked against escape. The perforate or wire mesh discs or washers do not provide a sufficient mass of metal to have an appreciable cooling effect on the heated gases.

The general result of my novel structure is that the heated gases are quickly vented from the interior of the cartridge so that pressure upon the latter is so reduced as to prevent rupture or bursting of the same; are quickly reduced in temperature before their final escape so that little danger of igniting inflammable material exterior of the cartridge exists; and are so cooled and reduced in pressure as to finally escape noiselessly through the said vent openings or perforations of the ferrules.

My invention also contemplates the use of the steel wool or other like material in combination with suitable vents in the fuse con-

taining cartridge even though the filler powder is omitted from the structure, and the fuse element enveloped only by the air confined within the containing cartridge.

55

I claim:—

1. A fuse cartridge comprising a tubular container, metallic end ferrules closing the ends of said container, an internally disposed fuse element interconnecting said end ferrules, a granular filler powder enveloping said fuse element, at least one of said end ferrules having vent openings in its end wall, and a layer of metallic wool capable of rapidly conducting heat interposed between said vent openings and said filler powder, said metallic wool having a comparatively high melting point. 60

2. A fuse cartridge comprising a tubular container, metallic end ferrules closing the ends of said container, an internally disposed fuse element interconnecting said end ferrules, a granular filler powder enveloping said fuse element, at least one of said end ferrules having vent openings in its end wall, and a layer of steel wool of substantial depth interposed between said vent openings and said filler powder. 70

3. In a device of the kind described, a containing cartridge, a fuse element enclosed within said containing cartridge, said containing cartridge having vent means, a granular filler powder enveloping said fuse element, and a layer of steel wool interposed between said vent means and said filler powder. 80

4. In a device of the kind described, a containing cartridge, a fuse element enclosed within said containing cartridge, said containing cartridge having vent means, and a layer of steel wool arranged within said containing cartridge in back of said vent means. 90

In testimony, that I claim the invention set forth above I have hereunto set my hand this 21st day of August 1919.
